(57) CLAIM

The ornamental design for a hoof block as shown and described.

DESCRIPTION

FIG. 1 is an upper perspective view of a hoof block, showing our new design;

FIG. 2 is a lower perspective view thereof;

FIG. 3 is a top view thereof;

FIG. 4 is a bottom view thereof;

FIG. 5 is a right side view thereof;

FIG. 6 is a left side view thereof; and,

FIG. 7 is a front view thereof, the rear view being a mirror image thereof.

The broken lines in the figures illustrate portions of the hoof block that form no part of the claimed design.
